CLAIM

The ornamental design for a door panel extrusion, as shown and described.

DESCRIPTION

FIG. 1 is a top perspective view of the door panel extrusion which is broken in the center indicating indeterminate length, and

FIG. 2 is a bottom perspective view of the door panel extrusion shown in FIG. 1.

FIG. 3 is a top perspective view of an alternative configuration of the door panel extrusion which is broken in the center indicating indeterminate length; and,

FIG. 4 is a bottom perspective view of the door panel extrusion shown in FIG. 3.

1 Claim, 2 Drawing Sheets

FIG. 1

FIG. 2
